UNITED STATES PATENT OFFICE

EDWARD M. GAREY, OF BROOKLYN, NEW YORK

ILLUMINATING DEVICE

Application filed February 8, 1927. Serial No. 186,612.

This invention relates broadly to illuminating devices of the kind known to the trade as flood lights and spot lights, adapted to illuminate store windows, for instance, and other prescribed areas both indoors and outdoors. The invention also relates to reflectors for such devices.

One object of the invention is the provision of such an illuminating device which is inexpensive and simple to manufacture and which has an adjustability which is practically universal. To this end what may be termed the neck of the fixture, within which an incandescent lamp is disposed is formed in one piece 15 with the reflector and is adapted to receive, on the end opposite to the reflector, a removable cap or cover in which the lamp socket is concealed. The neck has facilities for ventilating the interior thereof and of the reflector 20 and it carries an ear by which it is clamped to a pedestal with provision for adjustment of the reflector axis at any angle in a vertical plane.

The invention also seeks to secure a closure 25 of a transparent character to the reflector in a simple and expeditious manner. To this end there may be placed over the rim of the reflector a sheet of transparent material either of glass or of a gelatinous substance which 30 latter may be stretched and clamped in place by a flexible ring capable of being snapped on over a flange on the rim of the reflector and retained thereon by suitable lugs.

The invention also has for its object the 35 provision of a reflector whereof the reflecting surface will break up or deflect the light rays so as to cause the light radiated therefrom to serve as what is known as a flood light over a wide area while at the same time affording 40 a concentrated ray at the center of intense illumination, i. e. a sort of combined spot and flood light. Accordingly, the reflector is formed of a thin stampable easily polished metal and a plurality of substantially prismatic irregularities are formed thereon so as 45 to break up a predetermined portion of the light rays to obtain the effect of a flood light while concentrating another portion of the light to intensify the center of the illuminated area. More particularly a plurality of sub-

stantially diamond shaped generally pyramidal convexities are pressed inwardly from the outer surface in predetermined formation.

The invention also seeks to provide a reflector which may be manufactured in a substantially simple manner, and which will serve as a more intense spot light. To this end similarly shaped irregularities are formed in the surface in the reflector but these irregularities are concavities instead of convexities. 55

These and other objects of the invention and the means for their attainment will be more apparent from the following detailed description taken in connection with the accompanying drawings illustrating a preferred embodiment of the invention, in which: 60

Figure 1 is a view in side elevation and partly in section showing an illuminating device according to this invention. 70

Figure 2 is a view in front elevation of the illuminating device.

Figure 3 is a fragmentary sectional view taken in the plane indicated by the line 3—3 in Figure 2 and looking in the direction of 75 the arrows.

Figure 4 is a fragmentary portion of the reflector when used as a spot light showing the surface provided with a plurality of concavities instead of convexities. 80

Figure 5 is a view on an enlarged scale showing a fragmentary portion of the support for the illuminating device.

Referring to the drawings the socket 10 for the incandescent lamp 15, is shown as contained within a socket cover 11 to and through the end of which the electrical conductor 12 is led. The socket cover 11 is adapted to telescope without or slide over a reduced end or flange 20 on the main barrel portion or 90 neck 13, the annular head 14 on the socket cover 11 abutting against and limiting the degree of insertion of the flange 20. Suitable bolts 6 pass through the end wall 7 on the neck 13 and position the socket 10 and 95 secure the socket cover 11 in place.

The neck 13 is flared outwardly to form an enlarged portion 16 for the reception of the filament portion of the incandescent lamp and is provided with a plurality of apertures or 100

vents 17 for the passage of cooling currents of air.

The neck 13 is supported by means of an ear 19 secured, as by screws or bolts 21, thereto and pivotally mounted as by the bolt 22 upon an upstanding ear 25 of a post 23 to which it is clamped for pivotal movement in vertical planes by the wing nut 24, the ears 19 and 25 being serrated or toothed, as at 28 and 30, respectively, to afford a plurality of adjustments about the axis in a vertical plane.

Post 23 is axially rotatable within a base 24 adapted to be secured in stationary position, as by screws, to the supporting surface, to which base the post 23 may be clamped in desired angular position by means of the clamp screw 26.

Integral with the receiving part 16 there is formed the parabolic reflector 18 which is preferably formed of thin stampable highly polished metal with an outwardly turned flange 27 disposed in a plane perpendicular to the axis of the reflector. The transparent closure 29 is held against this flange by an annulus, indicated generally at 31, and comprising a front flange 32 and a rearwardly extending flange 33 substantially at right angles to the flange 32 and formed with a plurality of lugs 34 pressed inwardly and adapted to be disposed behind the flange 27 on the reflector 18 to hold the annulus 31 on the reflector. This annulus 31 is formed of flexible material having a degree of elasticity, such as zinc, so that it may be readily snapped over the flange 27 and held in place by the inwardly pressed lugs 34.

The construction just described permits not only the retention of a sheet say of glass as a closure 39 for the mouth of the reflector 18 but a flexible sheet formed say of a gelatinous material, suitably colored, may also be retained as indicated in Figure 3, it being merely necessary to lay the sheet 29 over the mouth of the reflector 18 and snap on the annulus 31 thereover, the annulus serving to stretch the sheet of material and clamp the edges 36 thereof about the flange 27 as shown.

When used as a flood light the surface of the reflector 18 is broken up by a plurality of convexities which are formed by pressing inwardly spaced portions of the surfaces, as at 37. These convexities are formed in annular rows in quincunx formation and the size of the individual convexities decrease toward the narrow part of the reflector. The convexities are also disposed in radial rows as shown and are substantially diamond shaped in outline so as to form, in effect, pyramidal convexities having a diamond shaped base with a slightly longer axis of the diamond extending in a radial direction but with all edges of the individual pyramids rounded as shown at 39 and having the apex blunt or rounded or substantially curvilinear or

spherical so that the light rays from the incandescent lamp striking these irregular surfaces are diverted in different angles and mingle to form a light which is diffused over a wide area and suitable as a flood light.

The surface of the reflector thus broken up is particularly efficacious since it permits of the retention of a high polish on the interior of the surface so that no light is lost in the process of reflection while the greater part of the light rays are broken up and mixed by what may be termed a prismatic diffusion and the light is thrown from the reflector over a large area with very good intensity proximate the reflector without glare. At the same time due to the spacing and shape of the irregularities this reflector also projects a central beam of greatly increased intensity, that is, of an intensity greater than would result were the prismatic surfaces not present.

The same general configuration may be availed of to increase the intensity of the light and permit the use of this fixture as a spot light. I have discovered that I am equally able to press these diamond shaped substantially pyramidal figures outwardly from the interior surface of the reflector to form a plurality of prismatic depressions so that each irregularity is in effect turned inside out, and thus a strong light over a prescribed area may be focused while all objectionable glare is obviated.

It may thus be seen that a reflector has been provided which may be readily and economically manufactured and which will diffuse the light or concentrate it depending upon the use of concavities or convexities.

What I claim is:

1. An illuminating device comprising a reflector having an inner polished surface formed with a plurality of protuberances forming substantially pyramidal reflecting surfaces arranged in quincunx formation. 105

2. An illuminating device comprising a reflector having an inner polished surface formed with a plurality of protuberances forming spaced pyramidal reflecting surfaces formed with rounded edges arranged in radial rows. 110

3. An illuminating device comprising a sheet metal reflector having an inner polished surface formed with a plurality of inwardly pressed diamond shaped convexities arranged in quincunx formation. 115

4. An illuminating device comprising a reflector, a neck integral therewith and formed with an end of reduced diameter, said reduced portion co-acting with a socket cover which telescopes over said reduced portion, a socket disposed within the socket cover, a flange in the said reduced portion co-acting with the said socket by bolt means to secure the socket cover and socket in position. 120

In testimony whereof I affix my signature.

EDWARD M. GAREY. 130
